H. F. BECHMAN.
TUBULAR PLATE PRINTING PRESS.
APPLICATION FILED MAY 3, 1915.

1,147,920.

Patented July 27, 1915.

UNITED STATES PATENT OFFICE.

HENRY F. BECHMAN, OF BATTLE CREEK, MICHIGAN, ASSIGNOR TO DUPLEX PRINTING PRESS COMPANY, OF BATTLE CREEK, MICHIGAN, A CORPORATION OF MICHIGAN.

TUBULAR-PLATE PRINTING-PRESS.

1,147,920.

Specification of Letters Patent.

Patented July 27, 1915.

Application filed May 3, 1915. Serial No. 25,527.

To all whom it may concern:

Be it known that I, HENRY F. BECHMAN, a citizen of the United States, residing at Battle Creek, in the county of Calhoun and 5 State of Michigan, have invented certain new and useful Improvements in Tubular-Plate Printing-Presses; and I hereby declare that the following is a full, clear, and exact description thereof, reference being 10 had to the accompanying drawings, which form part of this specification.

This invention is an improvement in so-called tubular plate printing presses of the type illustrated for example in my Reissue 15 Patent No. 18,129 of July 12, 1910, and Patent No. 979,919 dated December 27, 1910; and the object of the present invention is to enable two impressions to be taken simultaneously from a single page tubular plate 20 and to enable the plate cylinder to be plated without having to disturb the axial adjustment or relation of the cylinders, and this I accomplish by arranging the impression cylinders at preferably diametrically 25 opposite sides of the plate cylinder and providing means whereby one or more of such cylinders may be rotatorially adjusted relative to the others, so that when it is desired to put plates on the plate cylinder, or remove plates therefrom, the cylinders can be turned to positions hereinafter described which will enable tubular plates to be slipped on or off the plate cylinder without at that time contacting with either impression cylinder; and the cylinders are then 35 returned to their normal relative operative positions, whereupon the impression cylinders will take impressions from the plates on the plate cylinder in proper sequence. 40 The invention is simple but very practical and it avoids the necessity of using movable bearings for the plate or impression cylinders, or of employing means for separating the cylinders laterally in order to 45 place plates on or remove them from the plate cylinder.

The invention will be clearly understood from the accompanying drawings and explanation thereof and summarized in the 50 claims.

In said drawings: Figure 1 is a diagrammatical plan view of two blanket or impression cylinders and an intermediate "tubular plate" cylinder adapted to coöperate there- 55 with; and the gearing between said cyl-

inders. Fig. 2 is an enlarged end elevation of Fig. 1. Fig. 3 is a diagrammatic sectional view showing one position of the cylinders when in printing or operative relation, and the plate cylinder plated. Fig. 4 60 is a similar view showing the cylinders adjusted to the relative positions necessary to enable plates to be put on or removed from the plate cylinder. Fig. 5 is a detail sectional view illustrating one means which 65 could be used to enable one of the impression cylinders to be turned rotatorially in its bearings without affecting the other cylinders.

In the drawings 1 designates a plate cylinder and 2, 2^a similar blanket or impression cylinders arranged at opposite sides thereof. The plate cylinder is adapted to carry "tubular plates" P such as described in my patent aforesaid, which plates are applied to the cylinder by slipping them endwise thereon, and are removed by pulling them endwise therefrom. For this purpose one of the bearings 1^a of the plate cylinder is made of less diameter than the cylinder 70 and may be supported by a narrow web 1^b from the adjacent impression cylinder bearing, as described in my aforesaid patent, such web substantially corresponding in thickness to the width of the slot in the 75 plate P, which slot corresponds to the margin desired between consecutive impressions taken from the said plate upon a web. The other end bearing of the cylinder 1 may be 80 of ordinary construction. 90

The plate cylinder is provided with a longitudinal rib 1^c on its exterior surface which corresponds in width to the slot in the plate 85 P and serves to prevent the plate turning on the cylinder, as described in my said patent. 95

The impression cylinders 2 and 2^a may be mounted in bearings 2^c of ordinary construction, so that said cylinders will be fixed axially, relative to the plate cylinder. Preferably I make the impression cylinders 100 twice the diameter of the plate cylinders.

Each impression cylinder may be of ordinary construction and provided with the usual blanket or packing. The blanket on cylinder 2 has its ends passed through a longitudinal slot 3 in the cylinder and attached to blanket take-up devices therein as usual. The cylinder 2^a is similarly provided with a blanket the ends of which are passed through a slot 3^a in said cylinder and se- 105 110

cured therein by the usual take-up devices. Such take-up devices being common and well known need no detailed description here.

5 The cylinders may be intergeared at one side of the machine by means of a gear 1^e on the plate cylinder 1 meshing with gears 4, 4^a, on the adjacent ends of the impression cylinders 2, 2^a. These gears are so proportioned that the plate and impression cylinders will rotate at the same peripheral speed; and as the impression cylinders are shown as of twice the diameter of the plate cylinder the latter makes two revolutions to each 10 revolution of the impression cylinders.

The gear 4 on a cylinder 2 is preferably loosely mounted on the shaft of said cylinder, as indicated in Figs. 1 and 4, but can be made fast thereto by any suitable means.

15 As shown in Fig. 4 said gear 4 may be provided with a radially movable key 4^c in its hub which may be engaged with any one of a series of key-slots 2^e in the shaft 2^d of cylinder 2, which key slots are preferably arranged 90° apart. The key 4^c can be moved in or out of engagement with a key slot without removing the gear 4 from shaft 2^d, or disengaging it from the gear 1^e on cylinder 1.

20 It will be understood that when in operative condition two webs can be printed simultaneously by said cylinders, one web indicated by dotted line w' (Fig. 3) being led between cylinders 1 and 2 and the other web, indicated by dotted line w², being led between the cylinders 1 and 2^a; the means for supplying and guiding the webs are well understood and do not require to be illustrated, as they would vary according to the design 25 of the press in which the invention is to be employed.

25 It will be seen that when the mechanism is normally operating the plate B will be at all times in contact with either one or both of the impression cylinders 2 and 2^a; the only time when it is not in contact with both impression cylinders being when one of the gaps 3 or 3^a in the impression cylinders 2 and 2^a comes opposite the plate on the plate cylinder; or when the gap in the plate on the plate cylinder comes opposite an impression cylinder. As the gaps are narrow the plate P is actually printing all the time when the press is in operation and for most of the time 30 impressions are being simultaneously taken therefrom by both the impression cylinders. When the cylinders are in normal operative relation however it is impossible to put the tubular plates on, or remove them from, the plate cylinder. Heretofore in order to plate such cylinder, or remove plates therefrom, it has been necessary to provide means for bodily separating the cylinders axially to provide sufficient clearance between the peripheries of the plate and impression cylinders.

35 cylinders to enable the plates to be applied to or removed from the plate cylinder. This necessitated a more or less costly construction of parts, and also involved the possibility of the cylinders having their axial alignment or adjustment affected by the shiftable bearings not being returned to exactly correct positions. In my present invention when it is desired to plate the cylinder or remove a plate therefrom neither the 40 bearings nor the axial adjustment of the cylinders is disturbed.

45 As indicated in Figs. 2 and 3 the plate cylinder 1 has its rib 1^f adjacent the periphery of the cylinder 2^a and diametrically opposite the gap 3^a in said cylinder; this is a normal operative relation of the cylinders 1 and 2. The cylinder 2 is also shown in normal operative relation to cylinder 1 in Figs. 2 and 3, and in the positions shown in said 50 figures the gap 3 (when the parts are in the position shown in Fig. 2) will be at the lowest side of the cylinder 2, or about 90° behind the gap 3^a in cylinder 2^a. When the parts are in normal relation therefore the 55 plate P cannot be put on nor removed from the cylinder. If it is desired to remove the plate P from the plate cylinder, or put a plate thereon, then the cylinders are rotated until the cylinder 2 is in the position shown 60 in Fig. 4. Then this cylinder 2 is disengaged from its gear 4 by withdrawing key 4^c from the key-slot 3^e; and then cylinder 1 and cylinder 2^a are further rotated while cylinder 2 remains stationary, until these 65 cylinders, 1 and 2^a, also reach the positions shown in Fig. 4, namely, until the gap 3 or cylinder 2 comes opposite the plate cylinder 1 and diametrically opposite the rib 1^f thereon. In this position of the parts (see Fig. 70 4) a plate P can be slipped endwise on or removed from the cylinder 1, because in such position the gap 3 in the cylinder 2 makes a sufficient break in the periphery of the cylinder 2 to allow the plate P to be slipped on the cylinder 1 without contacting with the blanket on the cylinder 2; and the marginal slot in the plate P (which engages rib 1^f) makes a sufficient gap in the periphery 75 of the plate P to prevent the latter contacting with the opposed periphery of the impression cylinder 2^a. Therefore when the cylinders are adjusted to the position shown in Fig. 4 the gaps provide sufficient clearance to permit plates to be placed on or withdrawn from the plate cylinder without clash, but in the normal relative positions of the cylinders it would be impossible to put the plates on or remove them from the plate cylinder without clash with one or both 80 of the impression cylinders.

85 After the plates are placed on the cylinder 1 in order to get the cylinder 2 back to normal position without clash the cylinders 1 and 2^a are turned until the gap in the plate

on cylinder 1 comes opposite the gap 3 in cylinder 2 as indicated in dotted lines in Fig. 4, then gear 4 is locked to cylinder 2 and the parts are ready for operation.

5 What I claim is:

1. In printing mechanism, the combination of a cylinder adapted to carry a tubular plate having a longitudinal marginal slot, a pair of impression cylinders adapted to 10 act with said plate cylinder, each impression cylinder having a longitudinal gap in its surface; and means permitting said cylinders to be shifted rotatorially so as to bring the slot in the plate opposite the periphery of one impression cylinder and bring the gap in the other impression cylinder opposite the plate cylinder, to permit a plate to be slipped on or off the plate cylinder without lateral displacement of said cylinders.

15 2. In a tubular plate printing press the combination of a cylinder adapted to carry single page tubular plates each having a marginal slot, a pair of impression cylinders 25 at opposite sides of the plate cylinder, each impression cylinder having a longitudinal peripheral gap corresponding in width to the marginal slot in the plate; with gearing between said cylinders, and means whereby 30 one of the cylinders can be turned independently of the other cylinders; so that the marginal slot in the plate will be opposite the periphery of one of the impression cylinders and the gap in the other impression cylinder will be opposite the periphery of the plate cylinder, whereupon tubular plates may be slipped endwise on or off the plate cylinder.

35 3. In a tubular plate printing mechanism 40 the combination of a cylinder adapted to carry tubular plates each having a longitudinal slot, a pair of impression cylinders

adapted to co-act with said plate cylinder and arranged at opposite sides thereof, each impression cylinder having a longitudinal 45 gap in its surface substantially corresponding in width with the marginal slot in the plate; and means whereby said cylinders can be turned out of normal printing relation so as to bring the gap in the plate opposite the periphery of one impression cylinder, and the gap in the other impression cylinder opposite the periphery of the plate cylinder, whereupon the plates may be slipped on or off the plate cylinder without 50 55 axial displacement of said cylinders.

4. In a tubular plate printing press the combination of a cylinder adapted to carry single page tubular plates and having a marginal slot, a pair of impression cylinders 60 at opposite sides of the plate cylinder and of greater diameter than the plate cylinder, each impression cylinder having a longitudinal peripheral gap corresponding in width to the marginal slot in the plate; gearing 65 between said cylinders, and means whereby one of the cylinders can be turned out of normal printing position relative to the other cylinders to enable the marginal slot in the plate to be brought opposite the periphery of one of the impression cylinders and the gap in the other impression cylinder to be brought opposite the periphery of the plate cylinder, in which position tubular plates may be slipped endwise on or off the 70 75 plate cylinder without clashing with the surface of either impression cylinder.

In testimony that I claim the foregoing as my own, I affix my signature in presence of two witnesses.

HENRY F. BECHMAN.
